UNITED STATES PATENT OFFICE.

EDWIN H. STEEDMAN, OF ST. LOUIS, MISSOURI.

NEEDLE-HOLDER.

1,155,378.

Specification of Letters Patent.

Patented Oct. 5, 1915.

Application filed February 6, 1915. Serial No. 6,558.

To all whom it may concern:

Be it known that I, EDWIN H. STEEDMAN, a citizen of the United States, residing at St. Louis, Missouri, have invented a certain new and useful Improvement in Needle-Holders, of which the following is a full, clear, and exact description, such as will enable others skilled in the art to which it appertains to make and use the same.

10 This invention relates to needle holders, and is an improvement on the needle holder described in the pending application for patent for improvements in surgical needle holders, filed by Edward W. Saunders and 15 Edwin H. Steedman on June 30, 1913, Serial #776,659.

One object of my present invention is to provide a needle holder of the general type described in said application, in which the 20 needle clamping jaws are so constructed that it is impossible for the needle to jump out of position or become released from the jaws accidentally during the operation of forcing the needle through hard or tough material 25 that offers great resistance to the passage of the needle.

Another object is to provide a needle holder that has all of the good features and characteristics of the needle holder described in said joint application, but which 30 comprises fewer parts and also parts which are of such design that the instrument can be taken apart easily and sterilized thoroughly.

35 Other objects and desirable features of my invention will be hereinafter pointed out.

Figure 1 of the drawings is a top plan view of a surgical needle holder constructed 40 in accordance with my invention. Fig. 2 is a side elevational view of same. Fig. 3 is a rear end view showing the parts of the instrument in their normal position, namely, gripping one end of the needle and protecting 45 the opposite end of the needle. Fig. 4 is also a rear end view showing one of the needle-operating members movable toward the other needle-operating member which grips the needle so as to expose or uncover 50 the point of the needle. Fig. 5 is a vertical, longitudinal sectional view taken through

the center of the instrument. Fig. 6 is a cross-sectional view taken on the line 6—6 of Fig. 1. Fig. 7 is a cross-sectional view taken on the line 7—7 of Fig. 2. Fig. 8 is a top plan view of portions of the needle-operating members partly broken away on the line 8—8 of Fig. 6, so as to more clearly illustrate the construction of the needle-clamping jaws on said members. Fig. 9 is a detail sectional view taken on the line 9—9 of Fig. 2; and Fig. 10 is a detail view illustrating the connection between the movable element of one of the needle-operating members and the spring that moves said element 60 upwardly so as to release the needle.

In general design the needle holder that forms the subject-matter of my present application is practically the same as the needle holder described in said Saunders and Steedman application, and consists of 70 needle-operating members that normally protect both end portions of the needle and which are adapted to be moved bodily toward and away from each other out of axial alignment with the needle, so as to enable the needle to be inserted in the material being sewed and thereafter drawn completely through said material, said needle-operating members being so constructed that 75 the act of gripping one end of the needle automatically releases the opposite end of the needle which had previously been gripped by the instrument.

Referring to the drawings, which illustrate the preferred form of my invention, A and B designate two coöperating needle-operating members of similar construction that are arranged parallel to each other, as shown in Fig. 1. Said members are mounted in such a manner that they can be moved bodily toward and away from each other out of axial alignment with the needle during the operation of sewing with the instrument, and they are so positioned with relation to each other that when they are separated or in their normal position, as shown in Fig. 1, both end portions of the needle C will be protected in such a manner that it is impossible for the point or the eye of the needle 100 to accidentally stick into the patient or into the hand of the surgeon using the instru-

ment. Each of said needle-operating members comprises a stationary part or body portion 1 and a movable part or needle-clamping means 2 that is adapted to be moved with relation to the stationary part 1 so as to clamp and release the needle, but which is combined with said stationary part 1 so that it moves laterally with same when the needle-operating member which said parts form is moved bodily toward and away from the other needle-operating member of the instrument. The stationary part or body portion 1 of each needle-operating member is provided at its front end with a needle-clamping jaw 3 and the coöperating movable part 2 is also provided at its front end with a needle-clamping jaw 4, said jaws having coöperating faces which are beveled in opposite directions, as shown in Fig. 8, so as to conform approximately to the cross-sectional shape of the needle, which is of substantially triangular shape in cross section, and thus cause the needle to be forced into engagement with bearing surfaces 2^a and 2^b on the movable part 2 of the needle-operating member when said jaws close. The movable part 2 bears against one side of the stationary part 1, and said parts are connected together in such a manner that the part 2 can move longitudinally with relation to the part 1, so as to open and close the co-operating needle-clamping jaws 3 and 4 on said parts, the movable part 2 of the instrument herein illustrated being provided with a laterally projecting lug 5 that fits in an open-ended slot 6 in the stationary part 1, as shown in Fig. 2, so as to guide the part 2 longitudinally with relation to the stationary part 1. A head 7 on the lug 5 that laps over the outer face of the stationary part 1 prevents the parts 1 and 2 from moving laterally with relation to each other. The movable part 2 of the needle-operating member A is also provided with a shoulder or abutment 4^a, as shown in Fig. 6, so as to position the needle axially and prevent it from creeping longitudinally in either direction, the shoulder 4^a of the needle-operating member A forming an abutment against which the eye end of the needle is forced when the needle is gripped, as described in said Saunders and Steedman application. In view of the fact that the needle is substantially triangular shaped in cross section, it would be possible for the needle to force the jaws 3 and 4 apart, in case the needle moved outwardly or away from the bearing surfaces 2^a and 2^b on the member 2 during the operation of forcing the point of the needle through tough or hard material. In order to guard against this and eliminate the possibility of the needle jumping out of position or becoming released accidentally from the clamping jaws 3 and 4 when the point of the needle is subjected to pressure in a direction tending to

cause the eye end of the needle to fulcrum on the member 2, I have provided one or the other of the jaws 3 or 4 with a portion that laps over the outer convexed side of the needle, so as to prevent it from moving away from the bearing surfaces 2^a and 2^b on the member 2 when the opposite end or free end of the needle is subjected to pressure or to a strain of the character mentioned. In the preferred embodiment of my invention, as herein illustrated, the stationary jaw 3 of the needle-operating member A is provided with a portion 103 that laps over the outer convexed side of the needle, as shown in Fig. 8, and thus prevents the inner curved side of the needle from moving out of engagement with the bearing surfaces 2^a and 2^b on the part 2 when the jaws 3 and 4 of the needle-operating member A are closed, the jaw 4 being provided with recesses or cut-out portions so as to receive the forwardly-projecting portion 103 on the jaw 3 that laps over the needle. 70 75 80 85

If desired the jaw 3 of the needle-operating member B can be provided with a similar portion 103, so as to eliminate the possibility of the point portion of the needle becoming released accidentally, in case the needle is subjected to an excessive strain tending to cause the point portion of same 90 to fulcrum on the part 2 of the member B during the operation of drawing the needle through the material, but it is, of course, not so essential to form the needle-operating member B in this manner, as the time when the needle is most likely to be subjected to strains of this character is when the point of the needle is being forced through tough or hard material. The laterally-projecting lug 5 on the part 2 that extends into the open-ended slot 6 in the part 1 is so positioned that it will strike against one side of the needle and move it longitudinally of the part 1 out from under the overhanging portion 103 on the jaw 3 during the operation 95 100 105 110 115 of opening the jaws 3 and 4, so as to release the needle. However, any other suitable means could be employed for forcing the needle out of the jaw 3, and therefore, I do not wish it to be understood that my invention is limited to the precise means herein illustrated for accomplishing this result. 120

The movable part 2 of each needle-operating member is provided with a handle 2^a that has more or less resiliency, and said handle is equipped with a depending tail piece 9 that is embraced by a pair of ears 8 on the handle portion of the stationary part 1. Instead of connecting the handle portions of the parts 1 and 2 together by means of a toggle link and employing a coiled expansion spring for raising the handle portion of the movable part 2, as in the needle holder described in said Saunders and Steedman application, I have con- 125 130

nnected the handle portions of the parts 1 and 2 of the needle holder herein shown in a novel manner that simplifies the construction of the instrument and enables it to be taken apart easily and sterilized thoroughly. As shown in Fig. 5, the depending tail piece 9 on the handle 2^d is provided with an inclined slot 10 which has an enlarged portion 10^a at its upper end. The ears 8 which embrace said tail piece support a pin 11 that passes transversely through the inclined slot 10 in said tail piece. When the handle 2^d is depressed this coöperating inclined slot 10 and pin 11 cause the part 2 to move to the left, looking at Fig. 2, thereby causing the jaw 4 to securely clamp the needle against the jaw 3 on the stationary part 1. When said handle 2^d is moved upwardly said coöperating inclined slot and pin will cause the part 2 to move in the opposite direction and thus release the needle, the upward movement of the handle 2^d being effected by a flat leaf spring 13 whose upper end is connected to the handle 2^d and whose lower end bears on the bottom of the guide-way or slot formed by the ears 8 that embrace the depending tail piece 9 on the handle. The spring 13 can either be permanently connected to the handle 2^d or detachably connected to same, it being preferable to detachably connect the spring and handle together so as to enable the instrument to be sterilized thoroughly. As shown in Figs. 5 and 10, the spring 13 is provided adjacent its upper end with a cross slot 13^a, and the handle 2^d is provided on its underside with a pin having a head 13^b that extends longitudinally of the handle, the slot 13^a in the spring being so proportioned that the head 13^b on said head will pass through same when the spring 13 is arranged at right angles to the handle 2^d. After the spring 13 has been slipped over the head 13^b on said pin and turned into a position longitudinally of the handle it will be impossible for the spring to become accidentally disconnected from the handle, but when it is desired to disconnect said parts this can be effected easily by simply turning the spring 13 into such a position that the cross slot 13^a therein extends longitudinally of the head 13^b of the pin on the underside of the handle 2^d. The purpose of providing the member 2 with a handle 2^d that has more or less resiliency is to insure the needle being firmly clamped when the jaws 3 and 4 are closed and also hold the pin 11 in operative position and facilitate the removal of same, the resiliency of the handle 2^d also tending to hold said handle in its depressed position. The act of depressing the handle 2^d causes said handle to be straightened out and placed under tension, as shown in Fig. 2, so that by the time the pin 11 enters the enlarged portion 10^a of the inclined slot 10 in the tail piece 9 the jaw 4 on the part 2 will be subjected to pressure in a direction tending to cause the needle to be securely clamped against the stationary jaw 3, the enlarged portion 10^a of said slot coöperating with the pin 11 to form 70 practically a frictional lock that tends to hold the handle 2^d in its depressed position. The pin 11 is mounted loosely in the ears 8 and is provided intermediate its ends with a reduced portion 11^a, as shown in Fig. 9, 75 which is of the same diameter as the width of the slot 10 in the tail piece 9. Consequently, it is impossible for the pin 11 to move laterally out of the ears 8 when the handle 2^d is in its raised position, and when the handle is in its depressed position with the pin 11 positioned in the enlarged portion 10^a of the slot 10. The resiliency in the handle causes one wall of the enlarged portion of said slot to bear against one side of 80 the reduced portion of the pin 11, thus bringing a solid portion of the tail piece 9 into such a position that it lies between the enlarged portions of the pin 11 and prevents said pin from moving laterally out of the 85 ears 8. To withdraw the pin 11 it is necessary to exert sufficient downward pressure on the handle 2^d when said handle is depressed to cause the enlarged portion 10^a of the slot in the tail piece 9 to register exactly with 90 the enlarged end portions of the pin 11, thus permitting said pin to be withdrawn. By forming the instrument in this manner I reduce the number of parts of the instrument and enable it to be taken apart easily and 95 sterilized thoroughly.

The handles 1^a on the stationary parts of the needle-operating members A and B are provided with coöperating lugs 23 and 24, through which a shaft 25 passes so as to pivotally connect the members A and B together, and thus permit the member B to be moved toward and away from the member A, and vice versa. A flat leaf spring 26, which is arranged between the handles 1^a 105 and is securely connected at one end to one of said handles, tends to hold the members A and B separated, as shown in Fig. 1. Means are also provided for limiting the lateral movement of the members A and B 110 with relation to each other so that when said members are in their normal position, as shown in Fig. 1, the needle clamping means on the outer ends of said members will be positioned at the opposite ends of 115 the needle C. The instrument is provided with a guard 29 that lies under the handles 1^a of the members A and B, and means of the same construction as that described in said application of Saunders and Steedman 120 is employed for automatically locking said guard to the members A and B alternately during the operation of using the instrument so as to enable the user to more accurately control the lateral movements of the 125 130

members A and B. On the rear end of the shaft 25 is a tripping member 32 that lies underneath forwardly-projecting extensions 33 on the depending tail pieces 9 of the handles 2^d, said extensions coöperating with the tripping member 32 to raise the handles 2^d of the instrument so as to cause the needle-clamping jaws to open in the manner more clearly described in said Saunders and Steedman application.

Having thus described my invention, what I claim, and desire to secure by Letters Patent, is:

1. A needle holder provided with coöperating needle-clamping members, one of which can be moved relatively to the other, jaws on said members for gripping a needle, one of said jaws having a portion that hangs over the other jaw when the jaws are closed, and means for moving the needle from under the overhanging portion of said jaw when the jaws open.

2. A needle holder provided with a needle-clamping means composed of two members, one of which is adapted to be moved longitudinally of the other to clamp and release the needle, coöperating jaws on said members for clamping the needle, one of said jaws having an overhanging portion that laps over the other jaw when the jaws are closed and thus prevents the needle from moving laterally out of said jaws, and means for moving the needle away from the overhanging portion of said jaw when the jaws open.

3. A needle holder provided with a needle-clamping means composed of two members, one of which is adapted to be moved longitudinally of the other to clamp and release the needle, coöperating jaws on said members for clamping the needle, one of said jaws having an overhanging portion that laps over the other jaw when the jaws are closed and thus prevents the needle from moving laterally out of said jaws, and means for moving the needle away from the overhanging portion of said jaw when the jaws open, said means also serving to hold said members together and guide one member on the other.

4. A needle holder having a needle-operating member composed of a stationary part and a movable part provided with coöperating needle-gripping portions, and a device on one of said parts that projects into an inclined slot on the other part which is of such dimensions that the action of the side walls thereof on said pin will cause said movable part to move longitudinally of the stationary part when one end of said movable part is raised or lowered.

5. A needle holder having a needle-operating member composed of a stationary part and a longitudinally movable part provided with coöperating needle-gripping por-

tions, said movable part having a resilient handle, and automatic means for causing said handle to be held locked under tension when said coöperating needle-gripping portions are in engagement with the needle.

6. A needle holder comprising two elements, one of which can move with relation to the other, coöperating needle-gripping means on said elements, a resilient handle on one of said elements, and means that co-
operates with said handle to hold it under tension when the handle is depressed and thus cause said coöperating needle-gripping portions to securely clamp the needle.

7. A needle holder provided with two coöperating elements having needle-gripping portions, a resilient handle on one of said elements, and a slot and pin connection between said elements that causes one to move relatively to the other when said handle is depressed.

8. A needle holder having two members, one of which can move longitudinally of the other, coöperating needle-gripping means on said members, a resilient handle on one of said members, and a slot and pin connection between said members that effects longitudinal movement of the member provided with a handle and also holds said handle under tension when said handle is depressed.

9. A needle-holder provided with two coöperating members, one of which can move longitudinally of the other, a needle-gripping means on said members, a bifurcated portion on one member that embraces a guide on the other member, and a pin in said bifurcated portion that projects through an inclined slot in said guide which is of such dimensions that the action of the side walls thereof on said pin will effect a positive longitudinal movement of one member with relation to the other.

10. A needle holder provided with two coöperating members, one of which can move longitudinally of the other, a needle-gripping means on said members, a bifurcated portion on one member that embraces a guide on the other member, and a removable pin loosely mounted in said bifurcated portion and projecting through an inclined slot in said guide, said pin being provided intermediate its ends with a reduced section of less diameter than the portions of said pin which fit in said bifurcated portion, the diameter of said reduced section corresponding to the width of the main portion of said slot.

11. A needle holder having a needle-operating member composed of a stationary part and a movable part provided with coöperating needle-gripping portions, a resilient handle on said movable part provided with a depending guide, a bifurcated portion on said stationary part that embraces said guide, a pin in said bifurcated portion that

projects transversely through an inclined slot in said guide, said slot being provided at one end with an enlarged portion, and a spring acting on said handle in a direction tending to hold it in its elevated position.

5 12. A needle holder having a needle-operating member composed of a stationary part and a movable part provided with coöperating needle-gripping portions, a resilient handle on said movable part provided with a depending guide, a bifurcated portion on said stationary part that embraces said guide, a pin in said bifurcated portion that projects transversely through an inclined slot in said guide, said slot being provided at one end with an enlarged portion, and a leaf spring detachably connected to said movable part and having its free end bearing against said stationary part.

10 13. A needle holder having a needle-operating member composed of a stationary part and a coöperating longitudinally movable part, coöperating needle-gripping jaws on said parts, one of which jaws having an overhanging portion that laps over the other jaw and thus prevents the needle from being forced laterally out of position between the jaws, a resilient handle on said movable part which exerts pressure on said movable 15 jaw when a needle is gripped by said jaws, and a device on one of said parts that projects into an inclined slot on the other part whose edge bears against said device and causes the movable part to move longitudinally of the stationary part when one end of 20 said movable part is raised or lowered.

14. A needle-holder provided with coöperating needle-clamping jaws, one of which has a plurality of projecting portions that 25 lap over the dividing line between the jaws for the purpose described.

15. A needle holder having two coöperating members provided with needle-gripping portions, a resilient handle on one of said members provided with a guide that is arranged between a pair of ears on the other member, a pin loosely mounted in said ears and projecting through an elongated slot in 30 said guide which is enlarged at one point, and shoulders on said pin which normally bear upon opposite sides of said guide, said handle being adapted to be flexed so as to bring the enlarged portion of said slot into such a position that the shoulders on said 35 pin will not contact with said guide, thereby enabling the pin to be withdrawn from said ears.

16. A needle holder provided with two needle-operating members arranged in sliding engagement with each other, one of said members being adapted to move longitudinally of the other to clamp and release the needle, a jaw on one of said members that coöperates with a jaw on the other member, 40 said jaws having oppositely-inclined faces

that bear against the opposite sides of the needle and one of said members having a portion against which the inner side of the needle is forced when said jaws close, and a device on one jaw that laps over the dividing line between the jaws when the jaws are completely closed, said device having a surface that is presented toward the outer side of the needle and which is parallel to the portion on one of said members against which the inner side of the needle is forced when the jaws close.

17. A needle holder, comprising a needle-operating member provided with a rigid jaw that projects laterally from one side of same, 45 a bearing surface on the side of said member located adjacent said jaw that acts as a bearing surface for the inner side of the needle, a slideable jaw on said member that moves longitudinally of said member toward and away from said rigid jaw, said jaws being provided with oppositely-inclined faces that bear upon the opposite sides of the needle and force the needle into engagement with the bearing surface on said 50 needle-operating member, and a portion on one of said jaws that laps over the dividing line between the jaws when they are closed and which is provided with a surface that lies at approximately right angles to the inclined surface on said jaw that bears against the side of the needle.

18. A holder for a curved needle of triangular shape in cross section, composed of two needle-operating members arranged in 55 sliding engagement with each other, one of said members being longer than the other and provided at its outer end with a rigid jaw that projects laterally from the side of said member, said jaw having an inclined 60 surface that bears against one side of the needle, a flat bearing surface on said member against which the flat inner side of the needle bears, a jaw on the outer end of the other needle-operating member provided 65 with an inclined surface that bears against the other side face of the needle, and a portion on one jaw that laps over the dividing line between said jaws and fits in a recess in the other jaw when the jaws are closed.

19. A holder for a curved needle of non-circular shape in cross section, composed of two members arranged so that one can slide longitudinally of the other, a surface on one member against which the inner side of the 70 needle bears, coöperating jaws on said members having inclined needle-engaging faces that force the needle tightly against the surface on one of said members against which the inner side of the needle bears, and a device on one jaw that laps over the dividing line between the jaws and fits in a recess in the other jaw when the jaws are closed, one 75 jaw being subjected to resilient pressure when the jaws are holding a needle.

20. A holder for a curved needle, comprising relatively movable needle-operating members, and a needle-gripping means on each of said members comprising an abutment for the eye end of the needle, a surface against which the inner side of the needle bears, and coöperating clamping jaws that bear upon the opposite sides of the needle, one of said jaws having a portion that laps

over the other jaw and fits in a recess in same when the jaws are closed.

In testimony whereof I hereunto affix my signature in the presence of two witnesses, this 3rd day of February, 1915.

EDWIN H. STEEDMAN.

Copies of this patent may be obtained for five cents each, by addressing the "Commissioner of Patents, Washington, D. C."

It is hereby certified that in Letters Patent No. 1,155,378, granted October 5, 1915, upon the application of Edwin H. Steedman, of St. Louis, Missouri, for an improvement in "Needle-Holders," errors appear in the printed specification requiring correction as follows: Page 3, line 83, strike out the period and insert a comma, and commence the following article "The" with a small *t*, thus making a continuous sentence; same page, line 128, for the word "opeartion" read *operation*; and that the said Letters Patent should be read with these corrections therein that the same may conform to the record of the case in the Patent Office.

Signed and sealed this 2nd day of November, A. D., 1915.

[SEAL.]

R. F. WHITEHEAD,
Acting Commissioner of Patents.
